Serial No. 774,894

2 Claims. (Cl. 167—58)

1

The present invention relates to parasiticidal lotions for combating such body parasites as head and body lice.

Among the objects of the present invention is to provide a lotion which is quickly effective as a parasiticide, which is clear, homogeneous and stable, which manifests no adverse skin reaction, which is easy to apply and easy to remove, which is free from grease and which in general lends itself satisfactorily to the strictest pharmaceutical requirements.

In accordance with certain features of the present invention, the lotion comprises an aqueous suspension made of a pyrethrum extract as an active parasiticidal ingredient, a sesamin extract having a synergistic or activating action on the pyrethrins of the pyrethrum extract, apiol having insecticidal effect, dinitroanisole serving as an ovicide and benzyl alcohol which is a solvent for the ovicide and which affords an anaesthetic effect. The mixture also preferably contains perfume oils.

This mixture may be clear or cloudy depending for the most part on the wax content of the pyrethrum extract and on the solvent used in the manufacture of this extract. The dewaxed purified pyrethrum extract as used for aerosol bombs yields mostly clear mixtures.

In order to make the mixture described above emulsifiable, an intermiscible solvent has to be used. The solvent may be either oleic acid or a glycol fatty acid ester such as propylene glycol monolaurate or propylene glycol monooleate.

The resulting solution must be emulsified in water. The emulsifying agents for that purpose must be slightly acid and acid-stable to produce a lotion having a final pH of approximately 5.5-6.5 which is the range of optimum stability of pyrethrins. The emulsifying agents are desirably a combination of the following:

1. Sulfonated or sulfated oils such as castor oil, corn oil, cottonseed oil, etc.

2. Derivatives of hexahydric alcohol anhydride partial esters, namely sorbitan or mannitan monolaurate, such compounds being condensation products with ethylene oxide. The sum of such ethylene oxide linkages add up to 20 mols per mol of sorbitan or mannitan monolaurate.

3. Dioctyl sulfosuccinate and desirably the sodium salt, such as that described in the U. S. Patent #2,028,091.

For example, sulfonated oil may be combined with dioctyl sodium sulfosuccinate; sulfonated oil with derivatives of hexahydric alcohol anhydride partial esters; or the latter compound with

5 dioctyl sodium sulfosuccinate to produce the necessary emulsification.

The different ingredients of the lotion are dispersed in a diluent such as water. The resulting mixture aside from the emulsifying agents and the intermiscible solvent is not clear or stable, since it comprises a number of immiscible liquids. Therefore, to bring all of the ingredients of the mixture with water together in the form of a clear and stable emulsion, it has been found advantageous to employ two emulsifying agents and an intermiscible solvent.

10 The pyrethrum extract containing pyrethrins may be of any suitable type, and is desirably a dewaxed product containing about 20% pyrethrins. If the pyrethrum extract used yields a cloudy lotion, this can be corrected to produce a clear product by the use of additional organic solvents in a concentration of not more than 2% by weight at the expense of the water content of the formula. These solvents should be of such a nature as to prevent the waxes and polymerization products, as found in the commercially available pyrethrum extract, from precipitating out of the lotion. These solvents may be, for example, acetone, cyclohexanone, carbon tetrachloride, chloroform, alkylated naphthalenes and others.

15 The sesamin extract may contain in total from 11 to 25% of sesamin solids. The sesamin solids desirably contain an average of 90% of pure sesamin.

20 The apiol (dimethyl methylene ether of allyl tetroxybenzene) which is employed is desirably oleoresin of parsley fruit (liquid apiol). Apiol in this form has the advantage of not crystallizing out of the lotion. However, as far as certain aspects of the invention are concerned, crystalline apiol may be employed, although for lotion purposes, it is not as desirable as liquid apiol.

25 The apiol can be dissolved in the pyrethrum extract since the latter contains kerosene as a dissolving medium, in which apiol is also soluble.

Dinitroanisole is employed as an ovicide to destroy the nits or eggs of the parasites. Benzyl alcohol is used as a solvent for the dinitroanisole. This alcohol also has a slight anaesthetic effect which is desirable. Benzyl alcohol is also desirable for use as a solvent for the dinitroanisole, because a suspension of pure sesamin crystals in sesame oil was found soluble in benzyl alcohol.

30 The odor of the lotion may be improved by using a mixture of essential oils.

35 The following examples are illustrations of formulations in accordance with the present invention, but they are not to be construed as limiting the invention:

EXAMPLE 1

Using sulfonated oil and dioctyl sodium sulfosuccinate as emulsifying agents

	Percent weight/weight	5
Pyrethrum extract, dewaxed (20% pyrethrins)	5.0	
Apilo (oleoresin parsley)	0.5	
Sesamin extract	0.25	
Propylene glycol monolaurate	8.0	10
Dioctyl-sodium-sulfosuccinate	3.0	
Sulfonated corn oil, sulfonated castor oil or sulfonated cottonseed oil	20.0	
2,4-dinitroanisole	1.0	
Benzyl alcohol (free from chlorine)	8.0	15
Perfume oils	1.0	
Distilled water q.s. 100% (appr. 53.0)		

EXAMPLE 2

Using sulfonated oil and derivatives of hexahydric alcohol anhydride partial esters

	Percent weight/weight	20
Pyrethrum extract (as above)	5.0	
Apilo (oleoresin parsley)	0.5	
Sesamin extract	0.25	25
Propylene glycol monolaurate	5.0	
Sorbitan or mannitan monolaurate polyoxyalkylene derivatives	20.0	
Sulfonated corn oil or sulfonated castor oil	10.0	
2,4-dinitroanisole	1.0	30
Benzyl alcohol	8.0	
Perfume oils	1.0	
Distilled water q.s. 100% (appr. 47.0)		

EXAMPLE 3

Same as Example 2 except that propylene glycol monolaurate is replaced by 4% oleic acid and the water adjusted accordingly.

EXAMPLE 4

Using derivatives of hexahydric alcohol anhydride partial esters and dioctyl sodium sulfosuccinate

	Per cent weight/weight	35
Pyrethrum extract	5.0	
Apilo	0.5	
Sesamin extract	0.25	
Propylene glycol monolaurate	6.0	
Dioctyl-sodium-sulfosuccinate	13.0	
Sorbitan or mannitan monolaurate polyoxyalkylene derivatives	10.0	40
2,4-dinitroanisole	1.0	
Benzyl alcohol	8.0	
Perfume oils	1.0	
Distilled water q. s. 100% (appr. 50.0)		

EXAMPLE 5

Same as Example 4 except that the propylene glycol monolaurate is replaced by oleic acid 3.5% and the water is adjusted accordingly.

A procedure which may be employed for making a batch of the lotion in accordance with the formulation above set forth, is as follows:

1. Mix together dinitroanisole, sesamin extract and benzyl alcohol. If the resulting mixture is not clear after standing for a while, filter to get a clear solution.

2. Mix together the pyrethrum extract, apilo and the common solvent (either oleic acid or propylene glycol monolaurate) and add to solution from step #1. Add perfume oils and mix. In cases where the pyrethrum extract is of such a nature as to render the final lotion cloudy, add the additional solvent for the extract such as acetone, cyclohexanone or the like, as referred to above.

3. Add the two emulsifying agents and mix.
4. Add water and mix until a clear solution is obtained.

A pyrethrum lotion as described is thoroughly efficient and quickly effective in combating body and head lice, even in the most severe cases, is stabilized against decomposition, and remains clear and homogeneous indefinitely at temperatures above 15° C. When this lotion is applied, the lice die quickly. These applications are attended without dermatitis or skin irritation. The parasiticidal action of the lotion is decisive, and nits contacted with this lotion are killed and fail to incubate.

In the application of the lotion, one or two ounces of this lotion, applied, as for example, to the infected head of a person, is allowed to remain for about ten to fifteen minutes. At the end of that period, the medication may be removed with water, or if desired, soap and water may be used. It was found by this medication process, that the lice were killed, and that the nits did not incubate at the end of the hatching period.

Since the lotion of the present invention is clear and homogeneous, it is not necessary to shake it before use. In the case of a suspension which has to be shaken before use, there is no assurance that the active ingredients will be applied to the affected part in the right proportions. Furthermore, with a suspension, there are solid particles which are not easy to wash off. The lotion of the present invention, on the other hand, contains detergents which serve to produce foam so that the lotion works like a shampoo. A great deal of foam is produced in its application, and this carries all foreign matter out of the hair. In other words, the emulsifying agents serve not only to afford a clear lotion, but also permit said lotion with all the foreign matter attached thereto to be washed off. This is important where hair is being treated.

While the invention has been described with particular reference to a specific embodiment, it is to be understood that it is not to be limited thereto but is to be construed broadly and restricted solely by the scope of the appended claims.

What is claimed is:

1. A parasiticidal lotion for body parasites containing pyrethrum extract, sesamin extract, apilo, dinitroanisole, benzyl alcohol, an intermiscible solvent for said ingredients, water and emulsifying agents to form a clear, stable, homogeneous lotion, said intermiscible solvent being oleic acid and said emulsifying agents including a sulfonated oil and dioctyl sulfosuccinate.

2. A parasiticidal lotion for body parasites containing pyrethrum extract, sesamin extract, apilo, dinitroanisole, benzyl alcohol, and intermiscible solvent for said ingredients, water and emulsifying agents to form a clear, stable, homogeneous lotion, said intermiscible solvent being oleic acid and said emulsifying agents including a derivative of hexahydric alcohol anhydride partial esters and dioctyl sulfosuccinate.
